UNITED STATES PATENT OFFICE.

WILLIAM BARBOUR, OF OXFORD, IOWA.

STOCK-WATERING TANK.

No. 809,928.

Specification of Letters Patent.

Patented Jan. 16, 1906.

Application filed April 18, 1905. Serial No. 256,271.

To all whom it may concern:

Be it known that I, WILLIAM BARBOUR, a citizen of the United States, residing at Oxford, in the county of Johnson and State of Iowa, have invented certain new and useful 5 Improvements in Stock-Watering Tanks, of which the following is a specification.

My invention relates to stock-watering tanks, and to that particular class provided 10 with heaters which prevent the water from freezing in cold weather.

The object of my invention is to provide a tank with a heater so disposed as to utilize 15 the heat from the products of combustion to prevent the freezing of the water contained in the open trough.

With these and other objects in view the present invention consists in the combination 20 and arrangement of parts, as will be herein- 25 after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a longitudinal cross-section of my improved tank. Fig. 2 30 is a front elevation of the same, and Fig. 3 is a cross-section through the trough.

Referring to the drawings, in which like numerals of reference indicate corresponding parts throughout the several views, 1 is a reservoir, having an open trough 2 in communication therewith. In the embodiment of my 35 invention shown in the drawings this communication consists of a short pipe, to which is attached a valve 3, adapted to be opened 40 and closed as float 4 is lowered and raised by the water in the trough. Near the bottom of the reservoir 1 is provided a fire-box 5, having grate-bars 6 running longitudinally thereof.

7 and 8 are doors communicating with the fire-box and ash-pit, respectively.

Arranged under the trough 2 and running its entire length is a flue 9, communicating at one end with fire-box 5 and at the other with 50 smoke-pipe 10. The reservoir 1 is provided with a cover 11 to prevent the evaporation of the water and also to keep out the dirt. The reservoir is also provided with a cock 12, by which the water may be drawn off should ne-

cessity require it.

The operation of my device is as follows: Water supplied to the reservoir will pass into the trough outside, raising the float 4. When the predetermined depth of water is reached, the float will operate to close the valve 3, 60 which will remain closed until the level is reduced by water being taken from the trough by the stock. The products of combustion from the fire on the grate-bars 6 will pass over the rear wall of the fire-box down through 65 flue 9 and out of the stack 10, giving up their heat to the water above as they pass under the trough, thereby keeping the temperature of the water sufficiently high to prevent it from freezing. 70

The tank above described is simple in construction and can be maintained at a very little expense.

Having described my invention, what I claim as novel, and desire to secure by Letters Patent, is—

1. In a device of the character described a stock-watering trough, a water-reservoir adjacent thereto, a fire-box located near the bottom of said reservoir and a flue connected 80 with the said fire-box passing under the said watering-trough.

2. In a device of the character described a stock-watering trough, a water-reservoir adjacent thereto and in communication therewith, a float-actuated valve controlling the flow of water from the reservoir to the trough, a fire-box located near the bottom of the said reservoir, and a flue connected with the said fire-box passing under the said watering-trough. 90

3. In a device of the character described a stock-watering trough, a water-reservoir adjacent thereto, a fire-box located near the bottom of said reservoir, and a flue connected 95 with the said fire-box extending horizontally and arranged and adapted to heat the water in the said watering-trough.

4. In a device of the character described a stock-watering trough, a water-reservoir adjacent thereto and in communication therewith, a float-actuated valve controlling the flow of water from the reservoir to the trough, a fire-box located near the bottom of said reservoir and a flue connected with the 105 said fire-box, adapted to convey the heated gases produced by the combustion in the fire-box adjacent to the water in the said watering-trough.

5. In a device of the character described 110

a stock-watering trough, a water-reservoir adjacent thereto, a fire-box located near the bottom of said reservoir and a flue connected with the said fire-box adapted to convey the 5 heated gases produced by the combustion in the fire-box adjacent to the water in the said watering-trough.

In testimony whereof I affix my signature in presence of two witnesses.

WILLIAM BARBOUR.
